UNITED STATES PATENT OFFICE.

EDMUND JORDAN, OF BROOKLYN, ASSIGNOR, BY MESNE ASSIGNMENTS, TO
THOMAS V. ALLIS, OF NEW YORK, N. Y.

DIE FOR USE IN MAKING BARBED FENCING.

SPECIFICATION forming part of Letters Patent No. 450,077, dated April 7, 1891.

Application filed July 28, 1888. Serial No. 281,312. (No model.)

To all whom it may concern:

Be it known that I, EDMUND JORDAN, a citizen of the United States, and a resident of Brooklyn, in the county of Kings and State of New York, have invented certain new and useful Improvements in a Combination of Dies for Use in a Machine for Making Barbed Strips, of which the following is a specification.

- 10 My invention consists of improved contrivances of dies for producing two barbed strips from one double blank by making successive slits along the blank through the same in continuous connection, which slits are in two parallel lines and diagonal lines extending from one to the other of said parallel lines, making other slits in line with the parallel slits, which, together with the former slits, separate the barbed strips one from the other and form two barbs on each strip alternately, and then bending the barbs laterally to the strips for the required projection, and thus complete the production of two barbed strips with laterally-projected barbs
- 15 from one double blank without other dies for completing the separation of the barb-strips; and it includes a duplicate contrivance of the said dies for producing four barbed strips from two double blank strips, and it
- 20 also includes an improved contrivance of additional shearing-dies with said duplicate arrangement of dies for producing four barbed strips from a quadruple blank strip, all as follows:

- 25 Referring to the drawings, Figure 1 represents face views of the first slitting-dies and also of the lower series of following slitting and bending dies of my invention for cutting a double blank strip and barbing the resultant strips. Fig. 2 is a side elevation of the upper and lower dies with a blank strip between them. Fig. 3 is a diagram of a double blank strip, showing the action of the dies on it. Fig. 4 represents face views of dies, indicating the duplicate arrangement for producing four barb-strips from two double blanks or a quadruple blank. It also represents one of a pair of shearing-dies that may be employed subsequently to the making of the barbs for
- 30 separating the quadruple strip. Fig. 5 is a diagram of two double blanks, showing the ac-

tion of the duplicate system of dies on it. Fig. 6 represents face views of dies, indicating the duplicate arrangement, with contrivances for slitting the quadruple blank simultaneously with and by dies located between the dies that make the first slits. Fig. 7 is an end elevation of the dies for making the first slits and separating the quadruple blank, as seen looking in the direction indicated by the arrow in Fig. 6. Fig. 8 is a diagram of the quadruple blank as cut by the dies of Figs. 6 and 7.

I make a pair of shearing-dies *a b*, having the cutting-edges *c* along the middle portion, and *d* near each end in different parallel planes, and diagonal edges *e*, connecting the ends of said parts *c d*, respectively, the length of the whole of the cutting-edge being a little greater than the desired distance from center to center between the pairs of barbs to be produced on the finished strips, so that the successive slits completely separate the blank into two strips, and the distance of the planes of the edges *c d* apart is that of the desired width of the barbs to be made. These dies make, preferably, the first operation in the process of producing two barbed strips *f'* from a double blank strip *f*, though the order in which they are arranged with other following-described dies may be so changed that their operation is later. They cut the slits *c'*, *d'*, and *e'* through the strip *f*, corresponding with the shape of the dies, as above set forth, which slits so separating the blank also cut the barbs *l* along one edge and along the points. Next following are male and female parallel edged barbed cutting-dies *g h*, slitting through the strip in one direction—say upward—and similar dies *i j*, slitting through in the opposite direction, which dies, making the other slits *k* in line with and in extension of the parallel slits across the diagonal slits, separate the other uncut edges of the barbs *l* from the strips so far as they are to be cut therefrom, but leaving the uncut webs *m*, by which the barbs remain connected with the strips, two barbs (a pair) being connected by one web *m* alternately on each strip *f'*. These two pairs of slitting-dies together make four slits *k* to one slit *c' d' e'*, and together therewith make four barbs to each of said slits—that is, two barbs on each barb-strip—and they partly

bend the barbs into the required lateral projection, which is perpendicular to the plane of the strips and alternately in opposite directions. After the operation of these second 5 slitting-dies the strip thus completely cut for the barbs proceeds to the two pairs of bending-dies $n\ o$, suitably placed in the train for bending two of the cut barbs one way, and the other two reversely, which completes the 10 making of the barbs and the production of two barbed strips f' from a double blank strip.

The slitting and bending dies are duplicated, as indicated at $a'\ b'$, $g'\ i'$, and $n'\ o'$, 15 for converting two double blank strips f , Fig. 5, or a quadruple blank f^2 , Fig. 8, into four barbed strips at once, the duplicates being located side by side a suitable distance apart for so cutting the two double or one quadruple blank as will produce the said four barbed strips in the proper width, and when the quadruple blank strip is to be used a pair 20 of slitting cutters $w\ x$ is employed to separate the quadruple blank along the line z , 25 which slitting-dies may be arranged next in order with the benders, as indicated in Fig. 4, or they may be arranged in advance of the slitting-dies, if desired; but for a simpler and more compact arrangement for a shorter 30 range of dies they may be located between the duplicate slitting-dies $a\ b$ and $a'\ b'$, as represented in Figs. 6 and 7, where they cut the slit z abreast of the other slits.

What I claim, and desire to secure by Letters Patent, is—

1. The combination of shearing-dies, as $a\ b$, having the cutting-edges partly in two parallel and partly in two diagonal lines, as $d\ c$, and e , and being longer than the distance 40 from center to center between the pairs of barbs, and the two pairs of parallel edged dies, as $g\ h$ and $i\ j$, in line with the shearing-dies, together in the arrangement whereby these two forms of dies complete the production of two barbed strips from a double blank strip, substantially as described.

2. The combination of shearing-dies, as $a\ b$, having the cutting-edges partly in two parallel lines and partly in two diagonal lines, as $d\ c$, and e , and being longer than the distance 50 from center to center of the pairs of barbs to be made, the two pairs of parallel edged dies, as $g\ h$ and $i\ j$, in line with the shearing-dies, and two pairs of benders, as $n\ o$; all in the arrangement, whereby these three forms of dies complete the production of two barbed strips with laterally-projecting barbs from a double blank strip, substantially as described.

60 3. The combination of duplicate shearing-dies, as $a\ b\ a'\ b'$, having the cutting-edges partly in two parallel and partly in two diagonal lines, as $d\ c$, and e , and being longer than the distance from center to center between the pairs of barbs to be made, and the

duplicate parallel edged dies, as $g\ h$, $g'\ h'$, $i\ j$, and $i'\ j'$, in line with the shearing-dies, all in the arrangement whereby each range of these two forms of dies complete the production of two barbed strips from a double blank 70 strip or a quadruple strip, substantially as described.

4. The combination of the duplicate shearing-dies, as $a\ b\ a'\ b'$, having the cutting-edges partly in two parallel and partly in two diagonal lines, as $d\ c$, and e , and being longer than the distance from center to center between the pairs of barbs to be made, the duplicate parallel edged dies, as $g\ h$, $g'\ h'$, $i\ j$, and $i'\ j'$, in line with the shearing-dies, and the duplicate benders $n\ o$ and $n'\ o'$, also in line with the shearing-dies, and all in the arrangement whereby each range of these three forms of dies complete the production of two barbed strips having laterally-projecting 85 barbs from a quadruple blank, substantially as described.

5. The combination of duplicate shearing-dies, as $a\ b\ a'\ b'$, having the cutting-edges partly in two parallel lines and partly in two diagonal lines, as $d\ c$, and e , and the quadruple blank-slitting dies, as x , located between the duplicate shearing-dies, substantially as described.

6. The combination of the duplicate shearing-dies, as $a\ b\ a'\ b'$, having the cutting-edges partly in two parallel lines and partly in two diagonal lines, as $d\ c$, and e , the duplicate parallel edged dies, as $g\ h$, $g'\ h'$, $i\ j$, and $i'\ j'$, arranged in line with the shearing-dies, and the quadruple blank-slitting dies, substantially as described.

7. The combination of the duplicate shearing-dies, as $a\ b\ a'\ b'$, having the cutting-edges partly in two parallel lines and partly in two diagonal lines, as $d\ c$, and e , the duplicate parallel edged dies, as $g\ h$, $g'\ h'$, $i\ j$, $i'\ j'$, arranged in line with the shearing-dies, and the quadruple blank-slitting dies, as x , located between the duplicate shearing-dies, substantially as described.

8. The combination of duplicate shearing-dies, as $a\ b\ a'\ b'$, having the cutting-edges partly in two parallel and partly in two diagonal lines, as $d\ c$, and e , the duplicate parallel edged dies, as $g\ h$, $g'\ h'$, $i\ j$, and $i'\ j'$, arranged in line with the shearing-dies, the duplicate benders $n\ o$ and $n'\ o'$, also in line with the shearing-dies, and the quadruple blank-slitting dies, as x , located between the duplicate shearing-dies having the parallel and diagonal cutting-edges, substantially as described.

Signed at New York, in the county and State of New York, this 7th day of May, A. D. 1888.

EDMUND JORDAN.
